BOTTLE WIPING DEVICE FOR BOTTLE
VENDING MACHINESMax Hermann Voigtritter, Chicago, Ill., assignor
to Mills Novelty Company, Chicago, Ill., a cor-
poration of Illinois

Application October 21, 1937, Serial No. 170,231

4 Claims. (Cl. 15—210)

This invention relates to bottle vending machines of the type disclosed in my pending application, Serial No. 170,230, filed of even date here-with. Reference is made to that application for 5 description of the machine of which the device of the present invention forms a part, and the disclosure of that application is incorporated herein and made a part hereof by reference.

The object of the present invention is to provide 10 a novel bottle wiping device for removing a film of moisture from a bottle which has been stored in a bath of refrigerated water. More specifically, it is my object to provide a bottle wiping device which is adapted to operate automatically upon a 15 bottle as it issues through the discharge opening of a vending machine of the type above referred to. To this end, the invention provides a wiping device in the form of an annular collar of resilient material arranged in registering relation with the 20 delivery opening of the vending machine so that the bottle is forced to pass through the wiping device as it issues through the delivery opening. The internal diameter of the wiping collar is smaller than the maximum diameter of the bottle, 25 and arrangement is made for passing the bottle through the collar neck first, so that the shoulder portion of the bottle will spread the collar and cause the latter to tightly hug the surface of the bottle and wipe it dry with a squeegee action as 30 the bottle passes through.

A specific object of the invention is to provide a collar of such construction as to secure a maximum efficiency of wiping action, one which will not quickly lose efficiency through deterioration, 35 and one which may be easily repaired. This object is achieved by building up the collar from a plurality of rubber bands arranged on an annular spider in chord relationship to the spider so that the interior wiping edge of the collar is formed by 40 the central regions of the bands where they cross each other.

Other objects of the invention will become apparent from the following detailed description of a device embodying the invention when considered in connection with the accompanying drawing, in which:

Fig. 1 is a sectional view through a portion of a vending machine employing the invention;

Fig. 2 is a sectional view through the wiping device and flanged guide sleeve on which it is supported, showing a portion of a bottle passing therethrough;

Fig. 3 is a similar view without the bottle;

Fig. 4 is a plan view of the spider of the wiping 55 device;

Fig. 5 is a plan view of the wiping device in assembled relationship; and

Fig. 6 is a perspective view of one of the rubber bands used in building up the resilient collar of the wiping device.

Referring first to Fig. 1, the cover of the vending machine described in the pending application hereinbefore referred to, is designated generally by the reference character 10. In the cover 10 is a bottle delivery opening 11, defined by an annular collar 12 set into the cover 10.

Mounted upon a frame member beneath the cover 10 (the frame member not being shown) is a bracket 13 having a depending sleeve portion 14 formed integrally therewith. The sleeve 14 has 15 an integral guide skirt 15 extending downwardly therefrom. Said skirt and sleeve receive the bottle 16 from elevator mechanism 17 and guide it upwardly through the delivery opening 11.

Mounted upon the bracket 13 is a spider 18 of 20 sheet metal or any suitably stiff material, which has three openings 19 through which screws 20 are threaded into the bracket 13. The openings 19 are formed in depressed, cup-shaped bosses 21 formed in the spider 18, which serve the double 25 function of allowing the heads 22 of the screws 20 to be received in the plane of the spider 18 and forming feet to support the spider 18 in a position spaced above the bracket 13.

In the periphery of the spider 18 are a series 30 of equi-distantly spaced notches 23. Rubber bands 24 are stretched between spaced notches 23, each band embracing a portion of the periphery of the spider 18 and being arranged in chord relationship with respect to the spider. All the bands 35 are arranged so that their central regions are spaced equi-distantly inwardly from the inner edge of the spider 18. Thus the bands cooperate to form a resilient, readily distensible collar having a central opening 25, which is substantially 40 circular.

As the neck or shoulder portion of bottle 16 is forced through the collar opening 25, it will engage first the lower reaches of the bands and then the upper reaches thereof, stretching and spreading them until the collar has enlarged to the full diameter of the bottle. During this process, each band will be stretched and slightly curved around a small portion of the periphery of the bottle and will wipe that portion free of moisture.

Because the bands slide relative to each other and allow the collar to enlarge simply by bending laterally, the resistance offered to the passage of the bottle is negligible. At the same time the wiping action is very efficient.

It will be understood that the invention contemplates also the use of a solid collar of rubber or similarly resilient material arranged just below the delivery opening of the machine so as to discharge the moisture back into the liquid chamber of the machine, but a particularly efficient form is that shown wherein the collar is built up of rubber bands. One advantage of the rubber-band form over the solid collar is the fact that the collar formed by the rubber bands will not develop cracks in its interior periphery as would be possible in the deterioration of a solid collar, and thus is not subject to decreased wiping efficiency as would result from the development of such cracks.

Another advantage of the specific form of collar shown is that one of the rubber bands, if it breaks, may be quickly replaced.

A further advantage is the utilization of the common rubber band eliminating the necessity of employing rubber moulds for the formation of the collar.

It will be understood that the foregoing description is illustrative merely and is not to be taken as limiting the scope of the appended claims, to which reference should be made in order to determine the true scope of the invention.

I claim as my invention,

1. In a bottle wiping device for a bottle vending machine of the type in which the bottle, during a portion of its movement through the machine, is caused to move along its own longitudinal axis, a bottle wiping device comprising a resilient collar adapted to be disposed in such position that the bottle will be forced through said collar during such axial movement, said collar comprising a rigid spider in the form of a ring and a plurality of rubber bands stretched upon said spider in chord relationship to said ring, ex-

tending across the central opening of the latter, the central regions of said bands, where they cross each other, forming together a circular opening to receive the bottle.

2. In a bottle wiping device for a bottle vending machine of the type in which the bottle, during a portion of its movement through the machine, is caused to move along its own longitudinal axis, a bottle wiping device comprising a resilient collar adapted to be disposed in such position that the bottle will be forced through said collar during such axial movement, said collar comprising a rigid spider having a plurality of notches arranged in a circle, and a plurality of rubber bands stretched between said notches in uniform, chord relationship to said circle, the central region of said bands, where they cross each other, forming a circular opening to receive the bottle.

3. A bottle wiping device comprising a rigid spider in the form of an annular ring, and a plurality of rubber bands stretched upon said spider in uniform chord relationship thereto, the central regions of said bands, where they cross each other, forming a circular, distensible opening to receive a bottle.

4. A bottle wiping device comprising a bracket, a rigid spider in the form of a ring having a plurality of depressed bosses formed therein, said bosses being apertured, said spider being secured to said bracket by elements extending through said apertures and into said bracket, said bosses supporting the spider in a plane spaced above that of the bracket, and rubber bands embracing portions of the periphery of said spider and stretched thereacross in chord relationship thereto, their central regions, where they cross each other, cooperating to form a distensible, circular collar to receive a bottle.

MAX HERMANN VOIGTRITTER.
